UNITED STATES PATENT OFFICE.

JOSEPH VERTUNNI AND ORLANDO S. ELLER, OF LONG BEACH, CALIFORNIA.

SHOE-BUTTON REMOVER.

1,341,203.

Specification of Letters Patent.

Patented May 25, 1920.

Application filed April 30, 1919. Serial No. 293,997.

To all whom it may concern:

Be it known that we, JOSEPH VERTUNNI, a subject of the King of Italy, and ORLANDO S. ELLER, a citizen of the United States, both residing at Long Beach, in the county of Los Angeles and State of California, have invented a new and useful Improvement in Shoe-Button Removers, of which the following is a specification.

10 Our invention relates to the shoemaker's art and the object of our invention is to provide a device by which stapled buttons may be removed from shoes.

It is common practice in the art, at the present time, to attach buttons to shoes by means of a metal staple which is forced through the leather and clenched on the inside. It is often necessary to remove the staples, due to the buttons becoming lost or disfigured, or for the purpose of changing their positions on the shoes. Our invention comprises a novel tool which may be used by the shoemaker or cobbler for this purpose.

25 By referring to the drawings, which are for illustrative purposes only,

Figure 1 is a side view of our invention.

Fig. 2 is an end view.

30 Fig. 3 is a perspective view, showing the movements of the principal parts.

Fig. 4 is a view, on an enlarged scale, showing a commercial form of staple and button in place on a shoe, and

35 Fig. 5 is a view, on the same scale as Fig. 4, showing the method in which the staple is pulled from the shoe.

Our invention is shown in the drawings as embodying a hand tool such as may be commonly used by cobblers in small shops.

40 In these embodiments of our invention a pair of handle members 11 and 12 are employed, these members being mutually pivoted at 13 and held in their open position as shown in Fig. 1, by means of a flat spring 14. Formed at the forward end of the members 11 and 12 are jaws 15 and 16. Secured on the jaw 16 by means of screws 17 is a flat retaining plate 18 which is provided with a beveled slot 19 adapted to pass on either side of a staple 20 and under the eye 21 of a button 22, plate 18 being shown in Figs. 3, 4, and 5. Pivoted on the screw 25 and secured in the jaw 15, is a pulling wedge 26, having the form shown, and being provided with two prongs 27 and 28, the upper surface of the prong 28 being grooved

as shown at 29, the eye 21 of the button 22 sliding in this groove as the staple is pulled, as will hereinafter be explained. The pulling wedge 26 is held in contact with the 60 plate 18 by means of a flat spring 30.

The method of operation is as follows:

The flat plate 18 is slipped in place, the staple 20 sliding into the slot 19 as shown in Figs. 3, 4 and 5, and the pulling wedge is 65 driven across the plate 18 by pushing the handle members 11 and 12 together. The lower prong 28 of the pulling wedge 26 passes inside the staple 20 as shown in Fig. 5, pulling it out from the shoe which is held 70 in place by the flat retaining plate 18. The two prongs 27 and 28 are separated by a sharp edged groove, which is utilized to catch and hold the staple in the event one end lets go before the other. As this often 75 happens, this groove is quite essential to the proper operation of the device.

We claim as our invention:

1. A shoe button remover for pulling 80 stapled buttons from shoes comprising a retaining plate of proper shape and size to slip between the eye of the button and the surface of the shoe on either side of the staple; a pulling wedge of proper size to enter said staple under said eye and pull it 85 from the shoe; and means for forcing said wedge across said plate.

2. A shoe button remover for pulling 90 stapled buttons from shoes comprising a retaining plate of proper shape and size to slip between the eye of the button and the surface of the shoe on either side of the staple; a pulling wedge of proper size to enter said staple under said eye and pull it 95 from the shoe; said wedge being pivoted so that it may be swung against and away from said plate; spring means for holding said wedge against said plate and means for forcing said wedge across said plate.

3. A shoe button remover for pulling 100 stapled buttons from shoes comprising a retaining plate of proper shape and size to slip between the eye of the button and the surface of the shoe on either side of the staple; a pulling wedge of proper size to enter said staple under said eye and pull it 105 from the shoe; a member to which said plate is secured; and a second member pivoted to said first named member and carrying said wedge.

4. A shoe button remover for pulling 110 stapled buttons from shoes comprising a re-

taining plate of proper shape and size to slip between the eye of the button and the surface of the shoe on either side of the staple; a pulling wedge of proper size to enter said staple under said eye and pull it from the shoe, said wedge being pivoted so that it may be swung against and away from said plate; spring means for holding said wedge against said plate, a member to which said plate is secured; and a second member pivoted to said first named member and carrying said wedge.

5. A shoe button remover for pulling stapled buttons from shoes comprising a retaining plate of proper shape and size to slip between the eye of the button and the surface of the shoe on either side of the staple; a pulling wedge of proper size to enter said staple under said eye and pull it from the shoe; said wedge having a groove adapted to catch either end of said staple in the event that this end pulls free before the other end; and means for forcing said wedge across said plate.

10. A shoe button remover for pulling stapled buttons from shoes comprising a retaining plate of proper shape and size to slip between the eye of the button and the surface of the shoe on either side of the staple; a pulling wedge of proper size to enter said staple under said eye and pull it from the shoe, said wedge being pivoted so that it may be swung against and away from said plate; said wedge having a groove adapted to catch either end of said staple in the event that this end pulls free before the other end; and means for forcing said wedge across said plate.

15. A shoe button remover for pulling

stapled buttons from shoes comprising a re-

taining plate of proper shape and size to

slip between the eye of the button and the

surface of the shoe on either side of the

staple; a pulling wedge of proper size to

enter said staple under said eye and pull it

from the shoe; said wedge being pivoted so

that it may be swung against and away from

said plate; said wedge having a groove

adapted to catch either end of said staple

in the event that this end pulls free before

the other end; and means for holding said

wedge against said plate and means for forcing said wedge across said plate.

7. A shoe button remover for pulling 40
stapled buttons from shoes comprising a re-
taining plate of proper shape and size to slip
between the eye of the button and the sur-
face of the shoe on either side of the staple;
a pulling wedge of proper size to enter said 45
staple under said eye and pull it from the
shoe; said wedge having a groove adapted to
catch either end of said staple in the event
that this end pulls free before the other end;
a member to which said plate is secured; and 50
a second member pivoted to said first named
member and carrying said wedge.

8. A shoe button remover for pulling
stapled buttons from shoes comprising a re-
taining plate of proper shape and size to 55
slip between the eye of the button and the
surface of the shoe on either side of the
staple; a pulling wedge of proper size to
enter said staple under said eye and pull it
from the shoe, said wedge being pivoted so 60
that it may be swung against and away
from said plate; said wedge having a groove
adapted to catch either end of said staple in
the event that this end pulls free before the
other end; spring means for holding said 65
wedge against said plate, a member to which
said plate is secured; and a second member
pivoted to said first named member and
carrying said wedge.

In testimony whereof we have hereunto 70
set our hands at Long Beach, California,
this 22 day of April, 1919.

JOSEPH VERTUNNI,
ORLANDO S. ELLER,
